WARP BEAM CONSTRUCTION

Samuel A. Harris and Charles A. Sinquefield,
Winston-Salem, N. C., assignors to Briggs-
Shaffner Company, Winston-Salem, N. C., a
corporation of North Carolina

Application October 3, 1950, Serial No. 188,202

4 Claims. (Cl. 242—124)

1

This invention relates to improvements in warp beam or like constructions such as are used in the textile arts, and relates more particularly to improved means for obtaining a secure connection between the disc-like head and the cylinder or barrel.

Reference is made to the divisional and continuation-in-part application of Samuel A. Harris and Charles A. Sinquefield Serial Number 339,594, filed March 2, 1953.

It has been a problem in this art to mount the head securely with respect to the barrel so that the head will withstand the pressures caused by the material wound on the barrel and the strains caused by handling and use.

A principal object of this invention is to provide a novel joint between the barrel and the head which will withstand the forces to which it is subjected. Several representative embodiments of the invention are illustrated and described in the annexed drawings and following specification.

The invention is characterized generally by a novel connection including an expansible annular member or device, such as a collar or split ring, which is inserted into the bore of the barrel adjacent an end thereof, and expanded into contact therewith, means being provided to effect a locking connection of the annular member to the barrel. The expansible collar, member, or device forms part of a new and improved arrangement for connecting the head to the barrel. In certain forms of the invention, a hub is locked to the barrel, and the beam head is secured to the hub.

In the drawings:

Figure 1 is a central, vertical, sectional view of a construction embodying the invention;

Figure 2 is a central, vertical, sectional view of a modified construction;

Figure 3 is a central, vertical, sectional view of a further modified construction;

Figure 4 is a central, vertical, sectional view of still a further modified construction; and

Figure 5 is a reduced front elevation of the form shown in Figure 4.

The warp beam construction illustrated in Figure 1 comprises a barrel 10c and a head generally designated 11c at one end of the barrel. The opposite end of the barrel may be equipped with a similar head (not shown). The contacting faces of the barrel 10c and the periphery of a collar 13c within the barrel bore are provided respectively with registering annular grooves or recesses 12c, 12c', adapted to receive an expansi-

2

ble ring 23. The circular member or collar 13c is provided with radially disposed threaded sockets one of which is shown at 24 connecting the inner bore of the collar with the bottom of the recess 12c'. Set screws, one of which is shown at 25, threaded in the sockets 24 may be brought to bear against the inner wall of the ring 23 to expand it so that its outer portion enters the recess 12c formed in the barrel 10c. The head 11c, of plywood, is supported by a metal hub comprising inner and outer face plates 26 and 27, respectively, the inner face plate 26 having a flanged rim 26' which is frictionally seated within the bore of the collar 13c. The head 11c has a centrally disposed recess 11c' formed on its outer face, and the outer face plate 27 has a correspondingly shaped centrally disposed offset 27' which is seated in the recess 11c'. The two face plates 26 and 27 are securely connected together, with the head 11c between them, by means of bolts, rivets, or other suitable fastening means 28. The inner face plate 26, the head 11c, and the outer face plate 27 are provided with a common central bore, generally designated 29, into which the hub 20a of a gudgeon or stub shaft is inserted, the flanged portion 21a of the hub 20a being seated in a recess 19a formed in the outer face plate 27 within the offset 27'.

The beam head, forming a complete unit including the face plates 26 and 27, is secured as a unit to the collar 13c by bolts 17c passing through the face plate 27, head 11c, and into the threaded sockets 18c in the collar 13c.

In assembling the construction shown in Figure 1, the collar 13c, with the ring 23 seated in the recess 12c', will first be inserted in the bore of the barrel 10c, and the outer edge of the collar will be aligned with the edge of the barrel. As the recesses 12c, 12c' are located equal distances from the outer edges of the barrel 10c and the collar 13c respectively, the recesses will then register with each other. The set screws 25 may then be turned so as to expand the split ring 23, forcing it partially into the barrel recess 12c, the remaining ring portion remaining in the collar recess 12c'. The ring 23 thus acts as a key between the barrel 10c and collar 13c, effectively locking them together. The rim 26' of the face plate 26, with its attached parts, may then be seated in the bore of collar 13c, and the entire head unit secured to the collar by means of bolts 17c.

A modification is disclosed in Figure 2. In this construction, a circular flanged or rimmed

face plate member 26d is seated directly within the bore of the barrel 10d instead of within a separate collar as in Figure 1. The outer face 26d' of the face plate is spaced slightly inwardly from the end of the barrel, leaving the barrel end 5 projecting slightly for a purpose which will be described later.

The meeting faces of the bore of the barrel 10d and the collar part or rim 13d of the face plate 26d are provided respectively with oppositely disposed annular recesses or grooves 12d and 12d'. An expansible split ring 23d is seated in the recess 12d' of the rim 13d. The rim 13d is provided with radially spaced threaded sockets 24d, and set screws 25d are threaded in each 15 of these sockets. By turning the set screws 25d, the ring 23d is expanded radially so as to extend partially into the groove 12d formed in the bore of the barrel 10d, whereby the face plate 26d is firmly locked against movement with respect to the barrel 10d.

An outer face plate 21d is spaced from the face plate 26d by the head 11d which is positioned between the two face plates. As in the form shown in Figure 1, the hub 20d of a stub shaft or gudgeon is seated within a central bore provided within the face plates. The outer face plate 21d and the head 11d are secured to the face plate 26d, and thereby to the barrel 10d, by means of bolts 17d passing through the face plate 21d and being screwed into threaded sockets 18d provided in the rim or collar 13d. As shown in Figure 2, the end 10d' of the barrel 10d projects slightly beyond the outer face 26d' of the face plate 26d, so that as the bolts 17d are 35 tightened, the end 10d' of the barrel will bite into the adjacent wall of the wooden head 11d.

In the embodiments of the invention shown in Figure 3, and in Figures 4 and 5, the improved mounting of the beam head on the beam barrel is shown as being applied to a tricot beam. As shown in Figure 3, the bore of the beam barrel 10e is provided with an annular groove 12e. A circular member or collar 13e is fitted into the barrel past the groove 12e, the periphery of the collar being slightly smaller in diameter than the bore of the barrel so as to enter the bore with a slip fit. The collar 13e has a reduced annular recess 12e' with its marginal edge 12e'' slightly chamfered. A split ring 23e is seated in the groove 12e so that when the collar 13e is slid from the inside of the barrel outwardly towards the groove 12e, the shoulder between the collar portions of smaller and larger diameters engages the ring 23e, which thereby locks the collar against further movement towards the end of the barrel.

The beam head 11e is fitted over a hub 27e which enters the barrel bore with a snug friction fit, the hub having a flanged outer portion 27e' which lies flush with the outer face of the head 11e, being seated in an annular recess 11e' formed in the outer face of the head. The head is thus positioned between the end of the barrel and the flange 27e' of the hub, and as a unit is made fast to the barrel by means of cap screws 17e which pass through the hub at radially spaced points and are screwed into threaded bores 18e formed in the collar 13e. The cap screws are countersunk in the hub 27e so that their heads are flush with the outer face of the flange 27e'. The screws 17e pull the collar tightly against the ring 23e which is thus firmly locked in the recess 12e of the barrel. This form of the invention may readily be disassembled by loosening 75

ing and withdrawing the cap screws, permitting withdrawal of the hub so as to give access to the collar 13e. When the collar is pushed inwardly into the bore of the barrel 10e, the ring 23e will be exposed and freed so that it may be removed, after which the collar may be withdrawn from the end of the barrel.

In the embodiment shown in Figure 3, the barrel 10e is formed with a counterbore 10x which extends inwardly from the end of the barrel and forms a shoulder 10y which faces towards the adjacent barrel end, the annular recess or groove 12e being formed internally in the counterbored part of the barrel between the shoulder 10y and the barrel end. The distance between the shoulder 10y and the adjacent barrel end, axially of the barrel, is not less than and may be approximately equal to the dimension of the circular member or collar 13e axially of the barrel, whereby the collar may be moved to a position determined by its abutment with the shoulder 10y and in which position the collar is disposed axially inwardly of the recess 12e. This leaves the groove or recess 12e unobstructed so as to facilitate fitting of the ring 23e into the recess 12e. Furthermore, the shoulder 10y prevents the collar 13e from falling or sliding far enough toward the opposite end of the barrel to be out of reach of a workman assembling the parts.

In each of the constructions shown in Figures 9, 10 and 11, a radial face on the circular member is disposed within the barrel bore on the side of the ring remote from the adjacent barrel end. Consequently, when the securing screws are tightened, they hold the circular member against the ring, and hold the head structure against the barrel end.

In the form shown in Figure 4, the barrel 10f and head 11f structure is generally similar to that described in connection with Figure 3. Instead, however, of having a separate collar, the collar part or periphery of the hub 21f is provided with an annular groove 12f' corresponding in size with the groove 12f formed in the bore of the barrel 10f, and the groove 12f' is so positioned on the hub that when the latter has inserted its full length into the bore of the barrel, the two grooves 12f and 12f' will be aligned. Before assembly, a split ring 23f will be inserted into the hub groove 12f', the depth of this groove being at least equal to the radial thickness of the ring. The depth of the groove 12f' in the bore of the barrel is substantially less than the radial thickness of the ring. During assembly, when the grooves 12f and 12f' are aligned, the ring 23f is expanded into the barrel groove 12f' by means of set screws 25f disposed at circumferentially spaced points about the interior of the hub, access to the screws being obtained through an opening 28 in the hub 21f.

The beam head 11f is recessed on its outer face at 11f' to receive the flanged portion 27f' of the hub. The inner face of the head 11f is undercut slightly at 11f'' to receive the end of the barrel 10f. The head 11f is seated on the hub body between the end of the barrel and the flanged portion 27f' of the hub. After the hub 27f has been securely locked to the barrel by means of the set screws and ring, the head 11f is fixed against rotation with respect to the barrel by means of set screws 40 passing through the flange 27f' and biting into the head 11f.

The construction shown in Figures 4 and 5 may easily be disassembled if a springy split ring is used to lock the hub to the barrel. Running

back or removing the set screws 25f will permit the ring to snap or contract into the hub groove 12f so that the hub can be withdrawn from the barrel.

Changes in the construction and design may be made without departing from the scope of the invention as defined by the appended claims.

Having thus described our invention, we claim:

1. In a warp beam construction, a head, a barrel having a circumferential recess in the bore thereof spaced from the end of the barrel; a collar seated in said bore, means expandible into said recess to hold said collar against movement with respect to said bore toward said barrel end, the beam head comprising a disk having a hub portion extending into the bore of said barrel, and circumferentially spaced screws for securing said disk to said collar.

2. In a warp beam construction, a beam head, a tubular barrel, having an annular recess in the bore thereof adjacent its end, a collar seated in said bore, said collar having a diameter substantially the same as that of said bore, and having a recess at one end in alignment with the recess in said bore, a ring seated partially in each recess and keying said collar and barrel so that the collar cannot be displaced towards the adjacent end of the barrel, a flanged hub extending partially into said barrel, said head being seated on said hub between the hub flange and the adjacent end of the barrel, and circumferentially spaced screws for locking said hub to said collar.

3. In a warp beam construction, a tubular barrel having an annular recess formed internally adjacent an end of said barrel, an expandible ring expansion-fitted into said recess and projecting radially inwardly of the barrel bore, a circular member having a radial face disposed within said barrel bore on the side of said ring remote from said barrel end, a head structure at said barrel end and comprising a flange part and a hub part fitting snugly within said barrel

bore, and circumferentially spaced screws connecting said head structure to said circular member and holding said circular member against said ring and holding said head structure against said barrel end and holding said hub part in said barrel bore.

4. In a warp beam construction, a tubular barrel having a counterbore extending inwardly from an end of said barrel and forming a shoulder facing towards said barrel end and an annular recess formed internally in the counterbored part of the barrel between said shoulder and said barrel end, an expandible ring expansion-fitted into said recess and projecting radially inwardly of the barrel bore, a circular member having a radial face disposed within said counterbore on the side of said ring remote from said barrel end, a head structure at said barrel end, and means connecting said head structure to said circular member and holding said circular member against said ring and holding said head structure against said barrel end, the distance between said shoulder and said barrel end axially of said barrel being not less than the dimension of said circular member axially of said barrel, whereby said circular member may be moved to a position determined by its abutment with said shoulder in which said circular member is disposed axially inwardly of said recess, and fitting of said ring into said recess is facilitated.

SAMUEL A. HARRIS.
